(No Model.)

W. H. WOOLDRIDGE.
COOKING STOVE.

No. 431,158.

Patented July 1, 1890.

UNITED STATES PATENT OFFICE.

WILLIAM H. WOOLDRIDGE, OF BIRMINGHAM, ALABAMA.

COOKING-STOVE.

SPECIFICATION forming part of Letters Patent No. 431,158, dated July 1, 1890.

Application filed June 5, 1889. Serial No. 313,135. (No model.)

To all whom it may concern:

Be it known that I, WILLIAM H. WOOLDRIDGE, a citizen of the United States, residing at Birmingham, in the county of Jefferson and State of Alabama, have invented a new and useful Cooking-Stove, of which the following is a specification.

This invention has relation to cooking-stoves; and among the objects in view are to provide for a circulation of cold air around the fire-box, through the top and cross-pieces of the stove, whereby the life of the stove is extended, and the parts usually subjected to intense heat are maintained at a reasonable degree of temperature.

The invention consists in certain features of construction hereinafter specified, and more particularly pointed out in the claims.

Referring to the drawings, Figure 1 is a plan of a stove constructed in accordance with my invention. Fig. 2 is a side elevation. Fig. 3 is a central vertical longitudinal section on line *x* *x* of Fig. 1. Fig. 4 is a perspective of the two top sections of the stove. Fig. 5 is a similar view in detail of the stove plate or lid. Fig. 6 is a similar view of the fire-back.

Like numerals of reference indicate like parts in all the figures of the drawings.

1 represents the side walls of the stove, 2 the oven-door, 3 the fire-box, and 4 the ash-pit, all of the usual construction.

6 represents the front top section of the stove, and 7 the rear top section, each of which is provided with its respective removable cross-pieces 8 and 9 and pot-holes 10 at each side thereof. The rear edge of the section 6 is provided with a transverse downwardly-dependant offsetted portion 11, extending from side to side thereof, which portion is perforated or not, as desired, as at 11*, and at its center and opposite sides provided with laterally-disposed similar offsetted portions or branches 12. Upon the under side of the cross-pieces 8 and 9 there are provided longitudinally-disposed closed passages 13, which register and communicate with the adjacent branches 12, said passages 13 being open at both ends.

The section 7 is provided with, at its inner edge, an overlapping portion or plate 14, designed to take into a recess 15, formed at the inner edge of the offsetted portion 11, which

latter portion, in conjunction with the plate 14, forms a lateral passage open at both ends and communicating with the outer atmosphere by perforations 16, formed in the plate 14. The branches 12, extending from the passage 11, are covered by a projecting plate 17, extending from the edge of the plate 14.

Each of the stove-holes 10 at its outer sides or edges is provided with recesses 18, having a central perforation 19.

20 represents the stove-plate, which at one side is provided with a laterally-projecting arm 21, upon the under edge of which depends an L-shaped lug 22, designed to be received by the perforation or opening 19, formed in the recess 18, said recess being of a size and shape to receive the arm 21. By this it will be seen that when the plates 20 are not in use or serving their well-known function they may be partially revolved or rotated upon the lug 22, so as to project laterally from the side of the stove-top and serve as convenient shelves for the support of pots, pans, and other articles which it is desired to set aside, and in this manner I increase the area of my stove-top.

22' represents the fire-back, and the same is arranged in rear of the fire-box 3, and consists of two sections 23, each of which is a counterpart of the other, said sections being bolted together by bolts 24 and consisting of opposite registering offsets or corrugations 25, extending from each edge or side of the plates and slightly curved upwardly and to the center and terminating in the vertical flue 26, which is slightly curved or offsetted, as at 27, to communicate with an opening 28, formed in the center of the offsetted passage 25, and intermediate the two branches 12 thereof. Perforations 29 are formed on each side of the stove and permit cold air to pass through the passages 25 up into the flue 27, through the passage 11, and out through the branches 12 into the passages 13 of the cross-pieces 9, and thus sufficiently cool the stove.

The hot air that passes into the fire-back is discharged through the openings 16, formed in the rear top section 7, or, if desired, back into fire-box.

The oven-door 2 is provided at its upper rear corner with a pintle-rod 30, which takes the place of the usual pintle or bolt. Said

rod is extended through an opening or slot 31, formed in the stove-top, and terminates in a handle 32, projecting above the top, whereby said door may be operated from above the stove and without the necessity of stooping, as is usual. A boss 33 is formed upon the operating-rod 32 above the opening 31 and serves to cover that portion thereof unoccupied by the pintle-rod 30. The rod 30 is also 10 provided with a recess or slot 34 for the reception of a poker or lifter adapted to operate the door in lieu of the handle 32.

Openings, as 34^a, may be formed in the rear section of the fire-back for the purpose 15 of ventilating the oven, said openings preferably being covered with a suitable screen of wire-gauze.

Having described my invention, what I claim is—

- 20 1. The combination, with a stove, of a stove-top formed in sections, one of which overlaps the other, the opposite section being provided with a transversely-arranged passage having opposite branches covered by the opposite 25 section, and of cross-pieces mounted in the stove - openings and provided with open-ended air-passages communicating with the branches, substantially as specified.
2. In a stove, a fire-back provided with a 30 series of lateral air-passages communicating with the exterior and terminating in a vertical flue, substantially as specified.
3. In a stove, a fire-back formed of opposite 35 sections having air-passages communicating with the atmosphere and terminating in a central passage, in combination with a stove-top having a transverse air-passage communicating with the vertical flue of the fire-back and having opposite branches, substantially as 40 specified.
4. In a stove, a fire-back provided at opposite sides of its center with a vertical series of laterally-disposed air-passages and at its

center with a vertical passage, the inner ends of the lateral passages communicating therewith, substantially as specified. 45

5. The combination, in a stove, of the fire-back 22, having the inwardly-disposed series of oppositely-located air-passages 25, terminating in the central flue 27, with the top of 50 the stove formed in sections 6 and 7, the section 6 being provided with the offset 11, the central opening 28, receiving the flue 27, and the opposite branches 12, and the section 7 having the covering-plates 14 and 17, perforations 16, and the cross-pieces 8 and 9, having air-passages 13 communicating with the branches 12, substantially as specified. 55

6. The stove-top 6, having the opening 10, depression or recess 18, formed at one side 60 and extending therefrom, said recess 4 having the perforation 19 formed in its bottom, in combination with the plate 20, having the arm 21 fitting the recess, and the L-shaped lug 22, inserted in the perforation, the shank 65 of the lug acting as a pivot for the swinging of the plate, substantially as specified.

7. The fire-back consisting of two similar sections 23, bolted together and formed with opposite registering offsets or corrugations 25, 70 forming air-passages terminating at the center in the vertical flue 27, as set forth.

8. The sections 6 and 7, the first mentioned provided with the offset 11, having the branches 12, and the latter with the plate 14 and projecting portion 17, covering the offset and branches and forming air-passages, substantially as specified. 75

In testimony that I claim the foregoing as my own I have hereto affixed my signature in 80 presence of two witnesses.

WILLIAM H. WOOLDRIDGE.
